OPENABLE CLOSURE FOR CHAMBERS UNDER SUPERATMOSPHERIC INTERNAL PRESSURE AND ASSOCIATED FLUID PRESSURE MEANS FOR PREVENTING THE ESCAPE OF FLUIDS THEREFROM

Lambert Kooistra, Akron, Ohio, assignor to The Babcock & Wilcox Company, Rockleigh, N. J., a corporation of New Jersey

Application September 21, 1945, Serial No. 617,719

9 Claims. (Cl. 110—179)

1

The present invention relates in general to the construction and operation of closure members especially adapted for use with furnaces or other similar closed chambered structures operating under high internal gaseous pressures considerably above atmospheric and requiring access at intervals without necessitating a shut-down or causing interference with their prescribed functions. Structures suitable for the practice of my invention include boilers for example having a combustion chamber together with a communicating gas flow space wherein the gases of combustion are utilized mainly for the generation and heating of vapor. In other suitable structures the high pressure gases may be produced for various other purposes such as for utilization in processes or as a hot motive gaseous fluid for gas turbines.

In such installations the enclosing walls are often fluid cooled to provide protection from high furnace temperatures and further are preferably made gas-tight throughout to avoid the troublesome and dangerous condition resulting from the ejection of high temperature gases and other products of combustion. When a wall opening is provided through which access may be had to the interior for cleaning or other purposes it is essential that the opening be fitted with closure means suitably constructed and arranged so as to maintain the continuity of the gas-tight wall construction. Further, since it is essential in many instances to gain access to the interior during normal furnace operation, it is highly desirable to arrange in some manner to adequately control or to actually prevent the discharge of hot products of combustion when the closure means is removed or shifted to expose the opening.

There is an indication in the prior art that attempts have been made to restrict the escape of combustion gases through a furnace wall opening, in some instances through the use of air or steam jets directed either across the opening in the form of a screen, or into the opening toward the interior of the furnace. However, the prior art structures are inadequate for opposing the discharge of high pressure gases and moreover do not provide among other features the required interrelation between operation of the closure means and the initiation of jet action to assure complete control of gas discharge under all conditions.

An object of my invention therefore is to prevent the ejection of gases from a chamber where-

2

in the gases are maintained at superatmospheric pressures and an opening is provided affording access to the interior of the chamber.

A related object of my invention is the provision of apparatus adapted to open and close a furnace wall port while preventing the ejection of high pressure gas through the port throughout the opening and closing periods.

Another object is the provision of a closure member movable relative to a furnace wall opening whereby the escape of high pressure gas is prevented throughout substantially the entire range of closure member movement.

An additional object is to prevent the ejection of high pressure gas from a furnace wall opening by directing fluid toward the opening in a series of high velocity jets converging within a tapering passage of minimum flow area adjacent the opening.

20 An object is also to provide, in conjunction with a furnace operating under superatmospheric internal pressures and having an access opening in a fluid cooled wall thereof, means for preventing the ejection of hot products of combustion through the opening comprising a series of high velocity fluid jets converging inwardly toward the opening within a tubular member secured to tubes lining the wall, the tubular member constituting a frame for a door adapted to close the opening.

25 A further object is the provision of apparatus associated with a furnace wall opening whereby at one period a fluid under pressure is utilized to prevent the ejection of furnace gases through the opening and at another period is utilized to lock a cover in place over the opening.

Other objects include the provision of a closure member adapted to be moved into open and closed positions relative to a furnace wall opening and while the member is in the open position to prevent the ejection of high pressure gas from the furnace by a series of high velocity fluid jets controllable only when the member is in the closed position.

30 The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment 35 of my invention.

Of the drawings:

Fig. 1 is a side elevation, mainly in section, of the lower portion of a steam generating unit embodying my invention;

Figs. 2 and 3 are enlarged front and side elevations, respectively, of portions of the structure shown in Fig. 1; and

Fig. 4 is a plan section taken along line 4-4 of Fig. 3.

The steam generating unit illustrated in Figs. 1 and 2 is substantially the same as that disclosed in my copending joint application with H. J. Kerr et al., Serial No. 552,120, filed August 31, 1944, except for certain features peculiar to the present invention as will appear hereinafter, the unit including a cyclone type of primary furnace 10 from which the products of combustion flow into a secondary furnace 12. The walls of both furnaces are lined with wall cooling tubes suitably arranged and connected so as to form circuits paralleling the circulatory system of the boiler, the walls being of improved construction enabling the unit to be maintained under relatively high positive internal pressures throughout, as fully disclosed in the aforesaid prior application.

The cyclone-type primary furnace 10 is of horizontally elongated substantially circular cross section and preferably fired by a primary burner 13 arranged coaxially thereof in the outer end wall 14, the burner being of a suitable type for the kind of fuel to be fired which for present purposes may be assumed to be a crushed or granular fuel, such as bituminous or semi-bituminous coal. A stream of primary air and granular coal is delivered at a relatively high positive pressure through the involute curved primary air-coal pipe 15 which opens tangentially into a lower side portion of burner 13, the effective flow area of the pipe and thereby the velocity of the fuel-air stream being controlled by a manually operated control damper 16. The burner is constructed to impart a radial and forward motion to the entering coal-air stream and the whirling stream moves axially of the primary furnace in a helical path along and in contact with the circular wall 17.

A circular tertiary air chamber 18 is arranged

at the outer end of the burner 13 and a regulable supply of preheated air is delivered thereto through a duct 19 having an involute curved connection to the chamber 18, producing a whirling stream of tertiary air which is directed axially of the burner.

An axially elongated port 21 is provided for admitting secondary air to the primary furnace

10 at a point angularly spaced approximately

180° from the point of entry of the primary air-fuel stream, the secondary air being delivered to the port through a main air duct 23 having its end section fitting into and opening to the port 21, the velocity of air admission being controlled by a series of dampers 24 arranged to maintain the entering secondary air stream at all times along the primary furnace chamber wall.

In accordance with the previous disclosure, the primary air-fuel stream enters the furnace chamber in a high velocity stream whirling in a clockwise direction with an inner core of tertiary air whirling in the same direction. The fuel-air mixture rapidly ignites and the burning stream flows longitudinally of the furnace chamber at a high angular velocity in a film or layer following a helical path along and in close contact with the furnace circumferential wall. The secondary air

enters at substantially the same velocity and direction and gradually merges with the burning stream of primary air and fuel, without disrupting the helical flow path of the latter or separating the primary air-fuel stream from the circumferential chamber wall by a layer of secondary air. Combustion is substantially completed in the primary furnace chamber and the resulting hot gases are discharged through the coaxially arranged rearwardly flaring outlet throat 25 which is formed with an angle of flare of approximately 15° to its axis to provide minimum pressure drop therethrough.

According to one method of operation all of the combustion air may be supplied at a high positive pressure, e. g. 40 in. H₂O, to the primary furnace chamber and a decreasing positive pressure maintained throughout the remainder of the unit.

Openings are provided in the walls of the unit, at various positions, through which operation of the furnace may be observed and, if desired, a lance or other implement inserted to dislodge slag or other accumulations, or an oil burner or other device inserted to initiate the combustion of fuel introduced through pipe 15.

A suitable closure means for one of such openings is detailed in Figs. 3 and 4 where for simplicity of illustration an observation and lancing door 26 is shown as applied to an opening 27 between vertically extending tubes 28 associated with a side wall 29 of the secondary furnace 12. The wall 29 includes a metal casing 29a welded to the outer side of wall tubes 28 to provide with other walls of similar construction a completely sealed furnace chamber permitting operation at high positive furnace pressures. Doors of the same general type and function may be installed in various other positions, such as at the circled locations 31a, 31b, etc., in walls of the secondary furnace 12 and as indicated at 32a, 32b and 32c in a wall of the primary furnace 10.

The complete door assembly 26 comprises a tubular frame 34 terminating in a conical inner end portion 35 adjacent the opening 27 where it is secured as by welding to adjacent wall tubes 28. The frame is of circular internal cross section throughout providing a central passage 36 having its wall portion 37 adjacent the opening 27 of gradually reducing taper toward the opening, and its wall portion 38 remote from the opening of cylindrical formation, the tapering portion 37 extending in substantially tangential relation to tubes adjoining the opening 27 and being joined to the cylindrical portion 38 by an intermediate conical shoulder portion 39 facing the opening.

The door frame 34 is surrounded by a manifold 41 extending axially from the outer end of the frame to a location inwardly of the shoulder 39. Holes 42 are drilled through the inner wall of the manifold at the shoulder 39 for directing high velocity jets of air or other gaseous fluid into the central passage 36, the air for example being delivered under pressure of 80 p. s. i. to the manifold 41 through a pipe line 43 having a plug valve 45 therein. The jet holes or ports 42 are arranged in a circular row preferably at substantially equal circumferential spacings, the holes 42 being drilled from the front face of the manifold to provide an outer row of holes 46 in alignment therewith through which the inner holes 42 may be cleaned upon removing the plug screws 47. In certain constructions where it might not be possible to provide a corresponding

outer hole 46 for each inner hole 42, one or more of the holes 42 could if necessary be cleaned from inside the passage 36.

The frame 34 is symmetrically extended along its horizontal diameter to provide two substantially semi-circular extension portions 48 and 49, as shown in Fig. 3, each portion being formed with a cavity 51 as shown in Fig. 4 providing a continuation of the manifold space 41. The open side of each cavity 51 is closed by a plug 52 screwed into the front wall of the frame and its extension 48 or 49, the slot 52a facilitating assembly and removal. The plug 52 in extension 48 supports an axially movable hinge pin 53 about which the door plate 26a is pivoted, while the corresponding plug in extension 49 supports an axially movable catch pin 54.

Since the hinge pin 53 and catch pin 54 have similar mountings and are similarly actuated, a description limited substantially to the illustrated catch pin assembly will cover the essential features of both. Accordingly, and referring particularly to Fig. 4, the catch pin 54 extends outwardly from a manifold space 51 through a central hole 56 in plug 52, the pin having a slot 57 formed in one side thereof adjacent its outer end, the axial width of the slot being greater than the thickness of the door plate 26a at its circumferential edge 58. A disc 59 on the inner end of the catch pin 54 serves as a seat for a spring 61 having one end bearing against the disc and its opposite end against the inner face of the plug 52.

The spring 61 being under compression forces the catch pin 54 inwardly so as to cause the outer edge 62 of slot 57 to push against the outer face of the door adjacent one end of its diameter, while a similar spring 61 in extension 48 forces the hinge pin 53 inwardly so as to cause the cotter pin 63 through washer 64 to exert a corresponding force against the door adjacent the opposite end of its diameter. Thus with the door 26 in its closed position, as shown, and with a relatively low or zero fluid pressure within the manifold spaces 51, the springs 61 serve to lock the door firmly against its seat at the outer end of frame 34.

When the door 26 is in its closed position, the window 65 is centered over the outer end of passage 36 enabling operation of the furnace to be observed through the opening 27. In this position also, the hole 67 in the door is centered over the plug of valve 45 enabling a valve key or other tool to be inserted through the hole into engagement with the squared end 68 for manual control of valve operation.

When the door 26 is to be opened, the valve key is inserted through hole 67 and the valve turned on to admit high pressure air into the manifold 41, the air blowing through the jet holes 42 at high velocity toward the furnace wall opening 27 to prevent the ejection or blow-back of furnace gases. At the same time, the air pressure within the manifold forces both the hinge pin 53 and catch pin 54 outward, in opposition to the action of springs 61, whereby the door cover 26a is released from its seat. The valve key is then removed allowing the door to drop open and at the same time block access to air valve 45. The hinge pin 53 and catch pin 54 may each be formed with an enlarged intermediate flange portion 69 acting as a stop against the inner face of plug 52 to limit outward pin movement, in which case the extent of movement represented by space 71 is preferably less than the width of slot 57 to prevent the inner edge 72 from binding against

the inner face of the door plate 26a and possibly interfering with opening movement.

In closing the door the operations are reversed, first, the door plate 26a being swung into closed position over the door frame passage 36 bringing hole 67 again into alignment with the plug of air valve 45. The valve is then turned off shutting off the supply of compressed air to manifold 41, except for a small amount of cooling air that may be admitted, if desired, through a hole 73 in the plug of the valve. As a result of the accompanying drop in air pressure within the manifold, the springs 61 again force the hinge pin and latch pin inwardly to lock the door plate 26a in its closed seated position.

When a hole 73 is provided, the air admitted therethrough serves to prevent hot gases from entering the passage 36 behind the door plate 26a, thereby helping to keep the door cool, and supplementing the cooling effect on the entire door assembly resulting from the heat conducting engagement of the frame with the wall cooling conduits 28. Additionally, if any slight outward leakage should occur, the leakage will be of air rather than of hot furnace gases.

During the period that the door is open, the air blown from holes 42 is directed toward the furnace chamber in high velocity jets converging at a point 74 for example along the central axis 30 of passage 36 in a zone of reduced flow area such as at or adjacent the restricted throat passage 27 formed between wall tubes 28, the optimum point of convergence being determined, by test if necessary, with a view to rendering the jets 35 fully effective in overcoming the high static pressure of a given furnace under predetermined operating conditions.

The improved form of closure means herein disclosed is thus not limited in application to a boiler furnace operating at a positive pressure of the order of 40 in. H₂O, as indicated for the embodiment herein described, but may also be usefully applied to furnaces of various types operating at positive furnace pressures ranging upwardly to 90 or 100 p. s. i., wherein the problem of preventing the discharge of high temperature furnace gases becomes increasingly difficult. Furthermore, apparatus in accordance with this invention provides certain safety features which 40 are of particular importance with furnace pressures of the magnitude mentioned, for example, the door cannot be opened until after the air jets are in action and the required air pressure established within the manifold to release the door, 45 and secondly, the air cannot be turned off until the door is fully closed, thereby assuring complete and effective jet action throughout the entire period that the wall opening is uncovered.

I claim:

60 1. Closure means for a furnace wall access opening comprising a frame having an interior passage adapted to register with said opening, a cover movable into open and closed positions relative to said passage, means for directing gaseous fluid into said passage toward said opening in a series of high velocity jets converging along the central axis of said passage, and means responsive to a decrease and an increase respectively in the pressure of fluid forming said jets for locking and releasing said cover relative to said frame in the closed position relative to said passage.

70 2. Closure means for a furnace wall access opening comprising a frame having an interior passage adapted to register with said opening,

a cover movable into open and closed positions relative to said passage, means for directing gaseous fluid into said passage toward said opening in a series of high velocity jets converging along the central axis of said passage, and means responsive to a decrease in the pressure of fluid forming said jets for locking said cover relative to said frame in the closed position relative to said passage.

3. In combination with a wall structure having an opening therein to a chamber operable under superatmospheric internal pressure, closure means for said opening comprising a door movable into open and closed positions relative to said opening, means for establishing a fluid pressure zone adjacent the outer side of said opening for preventing the ejection of gases from said chamber when said door is in the open position, and means for controlling the supply of fluid under pressure to said zone, said control means occupying a position at one side of the path of movement of said door and being operable from a position at the opposite side of said path, said door having an opening therein through which said control means is rendered accessible for operation only when said door is in the closed position.

4. In combination with a wall structure having an opening therein to a chamber operable under superatmospheric internal pressure, closure means for said opening comprising a door movable into open and closed positions relative to said opening, means for maintaining a high velocity gaseous fluid flow through a zone adjacent said opening for preventing the ejection of gases from said chamber when said door is in the open position, means for controlling said gaseous fluid flow accessible for operation from a predetermined location when the door is closed, and means operable in response to movement of said door for rendering said control means inaccessible for operation from said location when the door is open.

5. Closure means for a furnace wall opening comprising a frame having an interior passage adapted to register with said opening, a door for said opening at the outer end of said passage, a manifold arranged annularly of said frame and having its inner wall portion in common with an outer wall portion of said frame, means for supplying fluid under pressure to said manifold, said common wall portion being provided with ports for directing said fluid into said passage in high velocity streams, a pin at one side of said passage forming a pivot support for said door, a pin at the opposite side of said passage forming a catch for said door, each of said pins extending into said manifold and functioning as a plunger movable in response to variations in fluid pressure within said manifold, means applying an inwardly directed force to each pin in opposition to the outwardly directed force resulting from exposure to said manifold fluid pressure, means associated with an outer end portion of each pin for clamping said door in closed position against said frame upon inward movement of said pins in response to a decrease in said manifold fluid pressure, and control means for varying said manifold fluid pressure.

6. Closure means for a furnace wall opening comprising a frame having an interior passage adapted to register with said opening, a door for said opening at the outer end of said passage, a manifold arranged annularly of said frame and having its inner wall portion in common with an

outer wall portion of said frame, means for supplying fluid under pressure to said manifold, said common wall portion being provided with ports for directing said fluid into said passage in high velocity streams, a hinge support for said door at one side of said passage, a catch for said door at the opposite side of said passage, said catch being movable from a door-engaging position when the door is closed to a position releasing said door for movement into open position, means for biasing said catch toward said door-engaging position for normally retaining said door in closed position, means responsive to an increase in the pressure of fluid supplied to said manifold for moving said catch into said door-releasing position, and control means for varying said manifold fluid supply pressure.

7. In combination with a furnace wall having an opening therein, closure means for said opening comprising a door at the outer end of said opening movable into open and closed positions, means for directing gaseous fluid under pressure into said opening toward the inner end thereof, means for controlling the pressure at which said fluid is directed into said opening, means operable in response to a decrease in said fluid pressure for locking said door in the closed position and in response to an increase in said fluid pressure for releasing said door for movement into an open position.

8. In combination with a wall structure having an opening therein to a chamber in which a superatmospheric pressure is maintained, closure means for said opening comprising a door at the outer end of said opening, means for directing gaseous fluid under pressure into said opening and effecting therein a gaseous fluid flow creating an inward suction at said outer end, means for controlling the pressure under which said gaseous fluid is directed into said opening, means operable in response to variations in said fluid pressure for locking said door in closed position upon a decrease in said fluid pressure and for releasing said door for movement into an open position upon an increase in said fluid pressure.

9. In combination with a wall structure having an opening therein to a chamber operable under superatmospheric internal pressure, closure means for said opening comprising a door movable into open and closed positions relative to said opening, fluid pressure means for preventing the ejection of gases from said chamber, means including a valve for controlling the operation of said fluid pressure means, and means responsive to movement of said door for preventing operation of said valve except when said door is in the closed position.
